KNIT FABRIC.

No. 18,610.

Patented Sept. 11, 1888.

UNITED STATES PATENT OFFICE.

GABRIEL UPTON, OF PHILADELPHIA, PENNSYLVANIA, ASSIGNOR TO CONYERS BUTTON AND MARTIN L. FINCKEL, OF SAME PLACE.

DESIGN FOR A KNIT FABRIC.

SPECIFICATION forming part of Design No. 18,610, dated September 11, 1888.

Application filed August 13, 1888. Serial No. 282,656. Term of patent 3½ years.

To all whom it may concern:

Be it known that I, GABRIEL UPTON, a citizen of the United States, and a resident of Philadelphia, Pennsylvania, have invented a new and original Design for a Knitted Fabric, of which the following is a specification.

My design is fully shown in the accompanying photograph.

The design comprises parallel transverse and longitudinal rows of fan-shaped or flaring bunches of threads, the contracted end of each bunch being adjacent to the flared ends of adjoining bunches, and the various bunches being connected by transverse chains.

I claim—

The design for a knitted fabric, substantially as described, and as shown in the accompanying photograph.

In testimony whereof I have signed my name to this specification in the presence of two subscribing witnesses.

GABRIEL UPTON.

Witnesses:

WILLIAM D. CONNER,
HARRY SMITH.
